CLAIM

The ornamental design for jewelry, as shown and described.

DESCRIPTION

1. Jewelry

FIG. 1.1 is an isometric view of jewelry, showing my new design;

FIG. 1.2 is a top plan view thereof;

FIG. 1.3 is a bottom plan view thereof;

FIG. 1.4 is a front elevational view thereof;

FIG. 1.5 is a rear elevational view thereof;

FIG. 1.6 is a left elevational view thereof; and

FIG. 1.7 is a right elevational view thereof.

The broken lines at the bottom and at the sides and top of the design are for the purpose of illustrating ornamentation which form no part of the claim.
